(57) **CLAIM**

The ornamental design for a transponder for telecommunication, as shown and described.

DESCRIPTION

FIG. 1 is a front elevation view of a first embodiment of a transponder for telecommunication, showing our new design;

FIG. 2 is a rear elevation view thereof;

FIG. 3 is a top elevation view thereof;

FIG. 4 is a elevation bottom elevational view thereof;

FIG. 5 is a right side elevation view thereof;

FIG. 6 is a left side elevation view thereof;

FIG. 7 is a front, bottom and right side perspective view thereof;

FIG. 8 is a front elevation view of a second embodiment of a transponder for telecommunication, showing our new design;

FIG. 9 is a rear elevation view thereof;

FIG. 10 is a top elevation view thereof;

FIG. 11 is a bottom elevation view thereof;

FIG. 12 is a right side elevation view thereof;

FIG. 13 is a left side elevation view thereof; and,

FIG. 14 is a front, bottom and right side perspective view thereof.

The broken line portion of the figure drawings is included to show unclaimed subject matter only and forms no part of the claimed design.
